AIR APPLICATOR

Donald Louis Minden, Los Gatos, Calif., assignor to
Lockheed Aircraft Corporation, Burbank, Calif.

Filed Apr. 8, 1964, Ser. No. 79,418

Term of patent 14 years

(Cl. D62—2)

FIG. 1

FIG. 2

FIG. 3

FIG. 4

FIGURE 1 is a perspective of the air applicator, showing my new design;

FIGURE 2 is a side elevational view of the air applicator;

FIGURE 3 is a top plan view of the air applicator; and

FIGURE 4 is a rear view of the air applicator.

The dominant features of the design reside in the portions shown in solid lines.

I claim:

The ornamental design for an air applicator, as shown and described.
